DESIGN FOR A HAIRDRESSER'S TINT TRAY

Lucy B. Melendez and Pedro Melendez,
Los Angeles, Calif.

Application July 12, 1948, Serial No. 147,506

Term of patent 14 years

(Cl. D86—10)

To all whom it may concern:

Be it known that we, Lucy B. Melendez and Pedro Melendez, citizens of Mexico and the United States, respectively, residing at Los Angeles, in the county of Los Angeles, State of California, have invented a new, original, and ornamental Design for a Hairdresser's Tint Tray, of which the following is a specification, reference being had to the accompanying drawings, forming part thereof.

Fig. 2 is a view in rear elevation of the same;

Fig. 3 is a view in side elevation of the same; and

Fig. 4 is a sectional view taken substantially upon the line 4—4 upon Fig. 1.

We claim:

The ornamental design for a hairdresser's tint tray, as shown.

LUCY B. MELENDEZ.
PEDRO MELENDEZ.
